UNITED STATES PATENT OFFICE.

JOHN J. MILLIN, OF NEW YORK, N. Y.

CARTON-WRAPPING MACHINE.

Application filed June 24, 1920. Serial No. 391,501.

To all whom it may concern:

Be it known that I, JOHN J. MILLIN, a citizen of the United States, and resident of New York, in the county of Kings and State of New York, have invented certain new and useful Improvements in Carton-Wrapping Machines, of which the following is a specification.

This invention relates to packing and wrapping machines and particularly to the part of mechanism manipulating the folded wrapper or carton to opening or squaring position prior to its being filled and closed.

The primary objects of my invention are the improved process of preparing or squaring the folded carton for the filling and closing operation, and means whereby my improved method is greatly facilitated.

The wrappers or cartons prior to undergoing the process of opening or squaring to filling position are usually shipped flat and folded at two corners. In order to open a carton to a square receiving shape the remaining two corners have to be bent. The necessary bending of the carton at these other or future corners is usually facilitated merely by lines impressed into the wrapper material. It is evident that such impressions do not suffice for the forming or opening of the carton to rectangular receiving shape, unless subjected to an operation, or operations positively defining and properly bending the future corners of the carton.

The methods and machines used heretofore tend to open the carton in a semi-positive manner by holding down one side and temporarily lifting up the folded-down free sides of the carton.

By merely lifting up the free sides to a temporary square position, a permanent square shape is not imparted to the carton. When such carton is filled and finally closed it will always have the tendency to tilt toward its originally folded position, due to the resiliency of the carton material, and it will assume a parallelogrammatic shape, which not only makes packing, shipping or storing highly inconvenient, but sometimes even impossible.

Heretofore the lifting was either done by pushing up from without one free carton side which is not parallel to that held down, in a semi-positive way, no matter whether or not the remaining corners were bent at their supposed bending line, or the folded

carton was opened with a "lifter" inserted between the held down side and the upper side which is parallel thereto.

By swinging up or otherwise raising the "lifter" the carton is unfolded, and forced to assume a temporary square shape. When using any one of these methods positive corners are not produced, which results as has been said previously in forming instead rectangular shapes, forms resembling more or less rhomboidal or parallelogrammatic shapes, depending upon the shape for which the carton is intended.

It often happens that the mechanism forcing the carton to a temporary square shape fails to function properly. In such cases irregular forms are created which prevent the proper filling of the carton, and greatly impairs the closing of the carton after filling it.

It is not unusual that besides the high percentage of spoilage due to improperly opened but not squared cartons, the breakage of the article to be packed is considerable, especially when frail merchandise like glass ornaments are handled. Also the loss of time caused by stopping the machine because of such breakage is considerable.

It is quite evident therefore that the proper packing operations largely depend upon correctly opening, permanently squaring and otherwise preparing the carton for the filling and closing operations, and that more efficient and less costly work may be done when the carton is properly made ready for receiving and retaining the merchandise.

In view of the foregoing the principle of my improved method will be more readily appreciated. It consists of not merely raising the free sides of a folded carton and temporarily holding it in square position, but of causing its corners to be of perfect and permanently rectangular shape. This can be accomplished only through actually bending or breaking the unbent corners of the delivered folded carton by completely reversing its original shape.

The process will be better understood by following each operation step by step.

A newly made, folded carton is placed with one of its sides on a plane surface and this side is held in its position. A bender blade is inserted in the carton and held in place at the obtuse corner formed by the

bent down carton side and by the adjacent held down side. Then the adjacent originally bent-down side is turned up and swung about the blade until completing substantially a half circle. Through this operation a perfect and acute corner is formed in place of the formerly indistinct obtuse corner. In consequence of the folding over of the one side, the parallel other side and the top side are placed in reverse position. In this way the four corners of the carton are so to speak, broken. Now the carton is released, and it will be found that it will assume, due to its own resiliency, a perfect or nearly perfect rectangular shape, which is far superior to any shape obtainable by applying the first mentioned two methods.

While my improved process of opening a carton to proper filling position may be accomplished by hand and by using primitive tools, it becomes necessary for quantity production to devise mechanical means properly designed and timed to substitute manual labor. Consequently, I consider it opportune and appropriate to inseparably embody in my invention not only my improved process, but also a machine adapted to accomplish the results sought by the process.

Therefore, further objects of my invention are to provide devices and mechanisms adapted to produce the desired results of opening cartons preparatory to filling and closing it.

The foregoing and still further objects of my invention will be more fully apparent from the following description when taken in connection with the accompanying drawings illustrating preferred embodiments of the invention and forming part of this specification.

In these drawings,

Figure 1 represents diagrammatically the various stages of a carton during my process of opening it to receiving position.

Figure 2 is a side elevation embodying a preferred construction of my device designed for accomplishing the results sought by my process.

Figure 3 is a plan view of the same.

Figure 4 is a sectional view taken on line 4-4 of Figure 3.

Figure 5 is a sectional view taken on line 5-5 of Figure 3.

Figure 6 is a sectional view taken on line 6-6 of Figure 3.

Figure 7 is a detail plan view of the bender blade mechanism.

Figure 8 is a sectional view therethrough taken on line 8-8 of Figure 7.

Figure 9 is a sectional view taken on line 9-9 of Figure 7.

Referring to Figure 1, in which a carton is shown in successive positions during the various stages of my process, the first position indicates a carton in its originally

folded shape which has just left the carton hopper. In this figure, I is the bottom of base carton side which is firmly held down (by means explained later), II is the folded-over carton side, forming with the held-down side an acute corner I', III is the bent-down carton side parallel to side II; and forming with the base-side an obtuse corner I'', IV is the top side parallel to base side I and forming with side II an obtuse corner 75 I''' and with side III an acute corner I''''.

The second position in Figure 1 shows a bender blade I inserted into the carton at the obtuse corner I'' while the base side of the carton is firmly held down. A re-folding lever 2 is shown below the bent-down carton side III ready to engage this carton side.

In the third position lever 2 is illustrated at its upward movement causing side III to 85 assume a vertical position, whereby the entire carton is squared. Lever 2 continues in its movement until side III is partially bent around the bender blade. Then folding or hold-down lever 3 commences to press down the carton until it is completely re-folded to the position shown in the fourth stage.

The formerly obtuse angles I'' and I''' now become acute, while formerly acute 95 angles I' and I'''' are now obtuse. In this way the carton corners are completely changed and "broken," and the shape of the carton is totally reversed.

When the re-folding of the carton is thus 100 completed the knife or bender blade 1 is withdrawn from the carton, the base side of the carton is released and the carton is pushed forward, in a manner explained later on, while being kept in its refolded 105 position by lever 3.

The carton travels forward and below deflecting curved guide 4 until it leaves lever 3. If the refolded carton would be totally released, it would assume a parallelogrammatic shape of its own accord.

In order to square the carton however, a spring operated straightening member 5 engages the now acute upper corner I''' and causes the carton to assume a rectangular 115 shape as shown in the last stage of Figure 1.

In this position the carton is ready to be filled and subsequently closed.

The foregoing description of the process mentions the use of mechanical means. The 120 underlying principle of refolding and releasing a carton may be accomplished, however, by purely hand operations.

When, as has been said before, rapid operations are required, the manual labor 125 would become impractical and a suitable machine is necessary to take its place.

Figures 2 to 6 illustrate preferred embodiments of my machine. A stand 6, upon which an operating table 7 is formed, sup-

ports the driving mechanism consisting of a transmission shaft 8 suitably lodged in bearings and driven by loose pulley 9.

The operation of shaft 8 is controlled by a 5 clutch device 10 adapted to engage pulley 9 when the machine is to be driven.

By way of pinion 11 and gear 12 power is transmitted to shaft 13 upon which are keyed cams 14 and 15 and a sprocket 10 wheel 16.

Cam 14 transmits its motion by means of connecting rod 17 and lever 18 to the longitudinally operating table mechanism, while cam 15 actuates by way of connecting rod 15 17' and lever 19, (Figure 5) a pair of gear segments 20 and levers 21, 22 and 23, the transversally operating table mechanism.

Sprocket wheel 16 drives sprocket wheel 24 of an article conveyer indicated at 25. (Figure 2.)

Fastened to the table at the end above the driving shaft is a carton hopper or guide 26 in which is placed a stock of flat folded cartons as indicated in dashed and dotted 25 line at 27. (Figure 3.) It will be noted that the lower closing flap 28 is at the left to the direction of travel from the hopper and forms an extension of the base-side of the carton.

30 A carriage 29 operated longitudinally by lever 18 and guided by stationary guide bars 29' is equipped with feeder plate 30 adapted to engage one folded carton at a time and to push it in front of the hopper. The carriage reciprocates, and at each forward stroke the carton is ejected from the hopper.

In order to stop the pushed-out carton from traveling back with the reciprocating carriage, gravity operated pawls 31 descend 40 behind the carton at the moment the latter leaves the hopper.

A lever arrangement 32 normally held in upward position by spring 32' and actuated by cam 32" attached to cam disc 15, operates 45 by means of shaft 33 the hold-down or refolding finishing lever 3. Between the carriage guide bars 29' is pivotally attached the carton refolding lever 2, provided with anti-friction rollers 2', adapted to be operated by guide blocks 34 provided at the 50 side of the lower carriage portion 34'.

When the carriage moves backwards the lever 2 is tipped over and is forced to press the bent-down side III of the carton partially up and around bender blade 1. When the carriage moves forward, lever 2 is released and brought to its inoperative position. In the meantime hold-down lever 3 descends, finishes the refolding operation of 55 lever 2, and keeps the carton in this new position until it has reached bent guide arm 4.

In order to prevent lever 3 from pressing down upon the carton too firmly, which may 60 interfere with its traveling forward, a stop

33' is provided at the upright part of lever arrangement 32, which passes through table 7, by means of stop screw 33" mounted in the table and adapted to engage stop 33'. The upward motion of lever 32 may be limited whereby the refolding operation of lever 3 is controlled. 70

At the end of feeder plate 30 are attached spring operated pusher pawls 35, normally held in upward position, and adapted to 75 push the refolded carton forward until it reaches bent guide arm 4 and assumes its squared position. When the carriage moves toward hopper 26 the pawls tip down and slide below the newly brought out carton 80 (by feeder plate 30) into operative position shown in Figure 6.

In a similar way to that of guide blocks 34, operates movable guide bar 36 which slidably rests on table 7 and which actuates, 85 in manner explained later, a series of interconnected carton pushers 37 by way of vertically movable pin 38. These pushers cause the forward motion of the filled cartons and are forced upwards by individual springs 90 39 or by any other suitable means when the carriage moves in forward direction. When moving in opposite direction pin 38 slides up the inclined edge 36' of bar 36 and exerts pressure against the short end of the first 95 pusher, thus causing it to tip down with its pusher end. The other pushers being interconnected follow this motion. (Figures 6, 8 and 9.)

Above the carriage an adjustable longitudinal carton guide frame 40 is provided and attached thereto is the curved carton guide 4 and a spring operated carton straightener 5, facilitating the opening of 100 cartons to filling or squaring position. 105 Guide frame 40 may be lifted when adjustments of the various mechanisms or the cartons are required.

Operated transversely to the direction of the travel of the cartons and adapted to slide 110 in the carton is bender blade 1, shown in detail in Figures 7, 8 and 9. As has been said above, the blade is actuated by lever 23 which causes it to move at a predetermined moment into operative position. 115

The bayonet-like blade is adjustably attached to slide 41 guided in a double frame 42.

Connected also with slide 41 at 43 is an 120 arm 44 bent down at its ends at 45 and 45'.

Parallel with the blade and guided in clamps 46 is the sliding guide bar 36, operating pusher pin 38. A spring 47 attached at 48 to one of the guide-clamps 46 and at 49 to the guide bar 36 tends to pull the latter toward the carriage. 125

At the moment, however, when the bender blade is withdrawn and the cartons are to move forward, being pushed by pushers 37, the pin 38 must be released. This is accom- 130

plished by the bent-down end 45 of arm 44 which moves with the blade in direction from the carriage. End 45 engages a set screw 50 provided at the up-turned end 51 of guide bar 36 and moves the latter with it.

In this manner pin 38 is caused to slide off from the other inclined edge 36" of guide bar 36. (Figure 8.)

When the blade travels forward again, 10 the guide bar 36 moves with it, due to the tension of spring 47. Pin 38 is forced to slide up again on edge 36" and forces pusher 37 down by pressing against its shorter arm. At the proper moment the motion of the 15 guide bar is arrested by pin 52, provided in table 7, (Figure 7), and stop 53 of the bar 36, while the blade continues in its travel.

Secured at 54 to one of the blade guide frames 42 and passing below bender blade 20 1 is a knife-like attachment 55 having an up-turned end 55' facing the carton hopper to which a carton closing flap-guide 56 is attached. See Figures 6, 7 and 8.

When the carton is fed forward from the 25 hopper, the carton flap-guide 56 tends to keep the closing flap of the carton below the level of the carton base-side which is to be firmly held in place during the refolding operation.

It also helps the flap being brought below attachment 55. This is facilitated by the turned up end portion of the latter.

Beneath attachment 55 is a flap clamping device consisting of lever 57 pivoted at 58 and equipped at one end with anti-friction roller 59 and at the other end with a platform 60, adapted to be pressed against attachment 55 by spring 61 holding the lever 57 down near its roller end. The spring is 40 conveniently fastened to the table.

The releasing of the carton flap takes place after the bender blade 2 has been withdrawn from the carton. This is accomplished by the bent-down end 45' of arm 44 45 attached to blade slide 41. Arm end 45' has a wedge-like extension 62 adapted to pass under roller 59.

When blade 2 has left the carton, blade slide 41 moves further until wedge 62 of 50 arm end 45' engages roller 59, thereby overcoming the tension of spring 61 and lifting the roller end of lever 57. Thus platform 60 is moved down and the carton flap is released. Now the carton is ready to travel again being pushed forward by pawls 35.

When the bender blade moves toward the next carton, the carton clamping device is first actuated, since wedge 62 releases roller 59 causing spring 61 to close the jaw or 55 platform 60.

In this manner the carton is first held firmly in position before the re-folding operation takes place.

A very important feature of my device is 60 a mechanism for adjusting the outlet of

the cartons pushed forward by the feeder. Cartons of various thickness may thus be stored in hopper 26 and their issue therefrom regulated. This is particularly desirable when cartons have swelled by 70 dampness.

The mechanism consists of a slide gate 63 provided at the delivery side of the hopper and operated by adjusting stud 64. (Figure 6.) 75

Operating simultaneously with, but in opposite direction to the bender blade, is a piston-like article feeder 65 which pushes the article to be wrapped from conveyer 25 into the opened carton. 80

The closing of the filled carton will be a subject of another application for Letters Patent.

The foregoing is a clear description of my improved process of preparing a carton for 85 its filling or squaring position by refolding or "breaking" its edges and the machine by means of which such process is greatly facilitated.

Having thus elucidated the objects of my invention and reserving for myself the right to make changes, improvements, additions, or construct entirely different, any or all, parts of my machine to suit various conditions and requirements, what I wish to cover 95 by Letters Patent and what I claim as my invention is:

1. A carton packing machine, comprising in combination, a frame and an operating table, said frame supporting the driving mechanism, said table supporting a carton magazine and carton manipulating devices operated by said mechanism, said device comprising co-acting central and sidewise actuated groups, said central groups consisting in part of a carton feeder, carton refolding members, carton squaring members, a stationary adjustable guide for guiding squared and filled cartons, and a plurality of carton pushers for keeping cartons moving forward at predetermined intervals, said driving mechanism comprising a pair of cams, actuated by way of a gear transmission, driven by a clutch-controlled, loose, driving pulley, a pair of connecting rods, a central lever for operating said co-acting central group connected with one of said rods, said sidewise actuated group comprising in part a bender blade adapted to reciprocate at given intervals in transversal direction to the direction of movements of said central group, a device for clamping one closing flap of a carton thus keeping the latter temporary in a dormant state during the refolding operation, a pusher controlling member, actuated in part simultaneously with said bender blade, a combination of levers operated by the other connecting rod and operating the aforesaid sidewise actuated group. 100 110 115 120 125 130

2. In a machine for the purpose described, comprising in combination, a hopper for storing a stock of folded cartons, a feeder adapted to engage one carton at a time and 5 to convey it forward in its folded position from the hopper, a stop device for retaining said carton in its forward position while the feeder travels backwards, a bender blade operated transversally to the direction of 10 travel of said feeder and adapted to pass in the carton at its lower obtuse corner, a clamping device for retaining a carton temporary in a dormant state and for holding down its base-side thus facilitating the un- 15 obstructed engagement of the obtuse corner of the carton by said blade, said obtuse corner being formed by said base-side and the adjacent free folded-down side of the carton, a refolding hook co-acting with the 20 feeder and adapted to engage said free side and to bend it partially around said blade, a cam and spring operated pressing lever for completing the refolding of the carton to a 25 position symmetrical and opposite to the original folded position thereof, and for keeping the carton in its newly refolded position while traveling forward, collapsible feeding pawls for pushing the carton forward in its refolded state, a curved receiver 30 arm for engaging the carton when ready to be straightened to its filling position, a spring operated straightening member adapted to engage the newly formed acute 35 upper corner of the carton and facilitating the latter to assume its open filling position, means for adjusting the down swing of said

pressing lever, and means attached at the lower portion of the hopper for regulating the carton outlet.

3. In a packing machine, the combination 40 of mechanisms for feeding, refolding or reversing, opening and squaring an originally folded carton, and for carrying and closing a filled carton, which comprises a feeder facilitating the ejection of a single carton 45 from a hopper, carton back stops, a bending member operating transversally to the travel of the carton and adapted to pass therethrough while in its originally folded position, refolding devices partially actuated 50 simultaneously with the feeder for bending a carton about said bending members into reverse position, and for keeping the refolded carton in its new reversed position while traveling forward, a carton receiver arm, a 55 spring actuated carton-straightening member, and a plurality of carrying members for engaging the filled carton, substantially as described.

4. In combination with a packing machine, 60 a carton refolding device comprising a bending member, a refolding member adapted to partially refold a carton side around said bending member, another refolding member adapted to finish the refolding operation of 65 the first refolding member, and regulating means for defining the degree of the final operation of said other refolding member.

Signed at New York, in the county of New York, and State of New York, this 70 18 day of June A. D. 1920.

JOHN J. MILLIN.
